SELF FEEDING MATCH CASE

Filed Oct. 20, 1928

Inventor

John F. Marx

By *Frank Keiper*
Attorney

UNITED STATES PATENT OFFICE

JOHN F. MARX, OF ROCHESTER, NEW YORK, ASSIGNOR OF ONE-HALF TO GERALD G. BURNS, OF ROCHESTER, NEW YORK

SELF-FEEDING MATCH CASE

Application filed October 20, 1928. Serial No. 313,890.

The object of this invention is to provide a new and improved pocket match case provided with an automatic device therein that will feed the matches from the case one at a time as the user of it may wish.

Another object is to permit the matches to be fed without opening the match case. Another object of the invention is to provide for the feeding of the matches one at a time by a new and simplified feeding device.

These and other objects of the invention will be illustrated in the drawings, described in the specification and pointed out in the claims at the end thereof.

15 In the drawing:

Figure 1 is a perspective view of my improved match case closed and viewed from the outside.

Figure 2 is a plan view of the match case 20 with the lid raised.

Figure 3 is a side view of the match case with the lid raised as shown in Figure 2.

Figure 4 is a section through the bottom of the match case, the section being taken on 25 the line 4^x, 4^x of Figure 2.

Figure 5 is a section on the line 5^x, 5^x of Figure 4 with the parts shown in normal position.

Figure 6 is a section on the line 5^x, 5^x of Figure 4 with the feeding device or ejector pulled back against the tension of the spring.

Figure 7 is an enlarged view of one of the claws by which the matches are engaged and fed.

35 It will be seen that the false bottom 7 does not completely cover the bottom of the box but leaves a slot 17 between it and the side of the box through which the bottom of the box and the jaw 9 is exposed. When the head 14 is moved to the position indicated by Figure 6 the jaw 9 travels along under the slot 17 for a certain distance as long as the spring 10 moves without making contact with the rivets 18 and 19 which are fastened in the bottom 40 of the box or are fastened between the bottom and the false bottom. When the spring 10 engages with the rivets 18 and 19 the spring is bent in as the head 14 moves on. This draws the ends of the springs toward each

45 other and pulls the jaw 9 away from the

flanged side of the box and pulls it under the false bottom 7.

The matches fill the box as shown in Figure 4 and if the box is tilted with the slot 17 down, the matches will gravitate in that direction 55 and one match will rest in the slot and rest on top of the jaw 9. When the jaw 9 is moved in the position shown in Figure 6 the match will drop to the bottom of the slot and when the head 14 is released the spring 15 will draw 60 the bow spring 10 to the normal position shown in Figure 5. In so doing the spring 10 will expand as soon as it is free from the rivets 18 and 19 and the jaw 9 will move out and engage the match that has dropped down 65 in the slot and will move it endwise with the jaw. It will cause the match to be fed out through the opening 20 in the corner of the box a half inch or more so that the user of the match case can take hold of the match 70 and draw it out of the box. This opening 20 is normally closed by the position of the jaw 9 to the extent that a match cannot drop out. The match can only get in position to pass through the opening 20 after the jaw 9 has 75 been moved to the position shown in Figure 6.

A jaw 21 similar to the jaw 9 can be put on the opposite end of the bow spring 10 and if a slot is left along the opposite side of the box corresponding to the slot 17 and the 80 opposite corner of the box is provided with an opening similar to the opening 20 a match can be fed from that side of the box by tilting that side of the box down and moving the button 14 in the manner above described. 85 In such case if the box is full and is held flat the box may feed two matches at the same time.

The box is provided with a roughened place indicated at 23 shown on the top 2 on which 86 the matches may be scratched.

In the drawings like reference numerals indicate like parts.

In the drawings reference numeral 1 indicates a metal box having a top 2 and bottom 3 of suitable dimensions hinged together on one side at 4. The top of the box neither constitutes or contains any part of this invention, it being simply a metal lid with a flanged edge that engages the flanged edge 160

of the bottom of the box, and locks thereto with a suitable clasp, which is formed by indenting both the bottom and the top as indicated at 5 and 6.

5 In the bottom of the box is placed a false bottom partition 7 which is raised above and separated from the bottom 8 so as to leave space between them in which the feeding and ejecting mechanism is held and in which it moves. This feeding mechanism consists of a jaw 9 mounted on one end of a bow spring 10 which is carried by a clip 11. This clip is made of sheet metal which is bent around the wire, the two sides of which clip 15 are fastened together by a rivet 12 which rivet extends through a slot 13 in the bottom of the box and has a large head 14 on the outside of the bottom by which the clip can be moved from outside the box and by which it holds itself in place. Fastened to the clip is one end of the spring 15. The other end of the spring is fastened to the false bottom 7 at 16. The normal position of the spring 15 and the bow spring 10 and the jaw 9 is shown in Figure 5. The operator takes hold 20 of the head 14 and draws the parts out to the position shown in Figure 6.

I claim:

1. A match box having a bottom and a 25 false bottom above it with a space between them, said false bottom being narrower than the box and leaving a slot between it and one side of the box through which a match can drop to the bottom, an ejector or feed mechanism below the false bottom consisting of a bow spring, a jaw carried on one end thereof adapted to slide along said slot as the bow spring is moved back and forth, a second slot in the bottom of the box by which the middle 30 of the bow spring is guided as it is moved back and forth, a handle attached to the bow spring and extending through the slot in the bottom of the box to the outside of the box by which the bow spring and its jaw may be 35 moved back and forth along the first named slot.

2. A match box having a bottom and a 40 false bottom above it with a space between them, said false bottom being narrower than the box and leaving a slot between it and one side of the box through which a match can drop to the bottom, an ejector or feed mechanism below the false bottom consisting of a bow spring, a jaw carried on one end 45 thereof adapted to slide along said slot as the bow spring is moved back and forth, a second slot in the bottom of the box by which the middle of the bow spring is guided as it is moved back and forth, a handle attached 50 to the bow spring and extending through the slot in the bottom of the box to the outside of the box by which the bow spring and its jaw may be moved back and forth along the first named slot, a pair of rivets fastened 55 between the false bottom and the bottom 60

adapted to be engaged by the bow spring near the end of its movement in one direction by which the bow spring is bent to bring the ends of its arms together, a tension spring 70 connected to said bow spring and to the stationary end of the box at the other end by which the bow spring is drawn to the other end of the box and normally held in position.

In testimony whereof I affix my signature.

JOHN F. MARX.
